US0D1056979S

(12) **United States Design Patent** (10) **Patent No.:** **US D1,056,979 S**
(45) **Date of Patent:** **** Jan. 7, 2025**

(54) **MODEL VEHICLE TRANSMISSION COVER**

(71) Applicant: **TRAXXAS, L.P.**, McKinney, TX (US)

(72) Inventors: **Kent Poteet**, Lucas, TX (US); **Otto Karl Allmendinger**, Rowlett, TX (US); **Adam Cole Ewing**, McKinney, TX (US); **Casey Christen Jens Christensen**, McKinney, TX (US); **Skylar Hagler**, Anna, TX (US)

(73) Assignee: **TRAXXAS, L.P.**, McKinney, TX (US)

(**) Term: **15 Years**

(21) Appl. No.: **29/886,309**

(22) Filed: **Mar. 7, 2023**

(51) **LOC (15) Cl.** **21-01**

(52) **U.S. Cl.**

USPC **D21/561**; D21/560; D21/562; D21/533

(58) **Field of Classification Search**

USPC D21/561, 562, 563, 565, 424, 495, 533

CPC A63H 17/262; A63H 19/18; B60G 7/003

See application file for complete search history.

(57) **CLAIM**

The ornamental design for a model vehicle transmission cover as shown and described.

DESCRIPTION

FIG. 1 is a lower, right, front perspective view of a model vehicle transmission cover showing our new design; FIG. 2 is an upper, right, rear perspective view thereof; FIG. 3 is an upper, left, front perspective view thereof; FIG. 4 is a lower, left, rear perspective view thereof; FIG. 5 is a front elevation view thereof; FIG. 6 is a rear elevation view thereof; FIG. 7 is a right side elevation view thereof; FIG. 8 is a left side elevation view thereof; FIG. 9 is an upper plan view thereof; and, FIG. 10 is a lower plan view of the model vehicle transmission cover.

In the drawings, the broken lines illustrate portions of the model vehicle transmission cover that form no part of the claimed design.

1 Claim, 6 Drawing Sheets
